[57] CLAIM

The ornamental design for a flexible clip, as shown and described.

DESCRIPTION

FIG. 1 is a front perspective view of a flexible clip, showing my new design;

FIG. 2 is a rear perspective view;

FIG. 3 is a front elevational view;

FIG. 4 is a rear elevational view;

FIG. 5 is a top plan view;

FIG. 6 is a bottom plan view;

FIG. 7 is a right side elevational view;

FIG. 8 is a left side elevational view; and

FIG. 9 is a cross-sectional view taken substantially along line 9—9 of FIG. 3.

FIGS. 3 through 9 have been drawn to an enlarged scale with respect to FIGS. 1 and 2.

FIG. 1.

FIG. 2.

FIG. 3.

FIG. 4.

FIG. 5.

FIG. 6.

FIG. 9.

FIG. 8.

FIG. 7.
